UNITED STATES PATENT OFFICE

2,350,945

TOOL FOR CUTTING LINOLEUM

Olmage Wesley Treadway, Little Rock, Ark.

Application September 10, 1943, Serial No. 501,859

6 Claims. (Cl. 30—294)

In the cutting and laying of wall linoleum, it is desirable that the joints between the sections be lapped so the seam is practically indistinguishable and the primary object of my invention is to provide a tool for cutting the linoleum with beveled edges so that such a seam may be formed when the linoleum is laid.

A further object of my invention is to provide a simple form of hand operated tool for this purpose.

Another object of my invention is to provide a hand operated cutting tool of the draw-cut type which when engaged with the linoleum automatically positions the cutting blade to produce a bevel cut in use.

Still a further object of my invention is to provide a tool of this character with a separate cutting blade that is removably and adjustably mounted therein.

Still another object of my invention is to provide a tool of this character that is adapted to use fragments of old safety razor blades as the cutting blades.

Other and further objects of the invention will be apparent from a detail description thereof, wherein only a preferred form of embodiment of the invention is shown and described, reference being had to the accompanying drawing, forming a part hereof, in which:

Figure 1 is a side elevation of my tool with the front edge of the draw head engaging a line indicating the top of the work;

Figure 2 is a bottom plan view of the tool with head sections open to receive a cutting blade; and

Figure 3 is a front end view of the tool in cutting position on the work.

The tool is of the hand operated draw cut type and includes a handle 1, generally formed of wood, in which is mounted a projecting metal shank 2 riveted in the handle and having the conventional metal ferrule 3. To the end of the shank 2 is secured the draw head of the tool designated in its entirety by the numeral 4. This head carries the cutting blade 5 in a manner to be hereinafter more fully described.

The head 4 is flat and in general configuration tapered at one end. The head 4 is formed of two sections 6 and 7 which in effect form clamping jaws to hold the cutting blade 5 therebetween as clearly shown in Figure 3. The sections are loosely secured together adjacent the tapered end of the head on a pin 8. This permits the sections at the front or work engaging end of the head to be swung away from and toward each other to permit the insertion and clamping of the cutting

blade 5. A screw bolt 9, mounted in the section 6, extends through and beyond the section 7. A wing nut 10 is threaded on the projecting end of the bolt to removably clamp the blade 5 in position in a manner that is obvious.

The edge of the section 6, adjacent the section 7, of the head 4, is undercut as shown at 11 to receive the end of the handle shank 2 and is rigidly secured thereto by a rivet 12. It will be noted in 10 the form shown, the head 4 is inclined with respect to the handle 1 and the front edge of the shank 2 is correspondingly inclined as clearly shown in Figure 1.

The front edge of the draw head 4 is transversely beveled as shown at 13 and rearwardly inclined at 14. This is the edge of the head that engages the work and the transverse bevel is best shown in Figure 3. The rearward incline 14 of the front edge of the head 4 is clearly shown in 20 Figure 1 wherein the dotted line 15 indicates the top of the work along which the tool is drawn. It will be noted the edge 14 is parallel with the longitudinal axis of the handle 1, when the tool is in operative position.

25 The blade 5, used with this tool, is very thin and may be a fragment of a safety razor blade. By the means employed for clamping the blade in the head 4, it may be easily removed therefrom to replace the blade when necessary. Also the blade is adjustable lengthwise between the sections 6 and 7 according to the depth of cut desired which depends upon the portion of the blade projecting from the head.

In use, the tool is positioned on the work comprising in this instance superposed layers of linoleum 16 and 17, as diagrammatically shown in Figure 1, and more in detail in Figure 3. The projecting portion of the blade 5 in this position cuts into the linoleum. One side of the head engages a ruler or other straight edge 18. When the front edge of the head engages the linoleum, the portion 14 lies flat thereon and the handle 1 is substantially parallel with and spaced from the work. The transverse bevel 13 tilts the head 4, 40 as clearly shown in Figure 3, and consequently the blade 5 is tilted with the head. When the tool is drawn along the straight edge 18 with the blade passed into the superposed layers 16 and 17 of linoleum, a beveled edge cut results. The 45 bevel cut may be varied according to the transverse bevel 13 to vary the inclination of the edges of the cut linoleum. It is obvious that layers of linoleum cut as described may be laid with lapped joints and the resulting seams are highly desirable in laying wall linoleum.

While this tool is particularly designed for forming lap seams for linoleum, it is adapted for other uses where a beveled or inclined edge is desired. The tool is so balanced and proportioned that it is very effective in operation and the fact the cutting blades may be made of discarded safety razor blades is an important feature tending to enhance the economy of operation. With this tool, layers of linoleum may be easily beveled before being laid to produce the desired lapped seams or joints with slight effort or loss of time.

I claim:

1. A device of the character described including a handle adapted to lie parallel with and substantially spaced from the work to be cut, a draw head at one end of said handle having one edge adapted to engage the work and being substantially parallel with the longitudinal axis of the handle, a cutting blade carried by said head and projecting from said edge into the work, and said edge being transversely beveled to tilt the head and blade laterally to produce a bevel cut.
2. A device of the character described including a draw head of appreciable width and thickness having one edge adapted to engage the work, a draw handle for said head, a blade projecting from the work engaging edge of the head, and said edge being transversely beveled to tilt the head and blade laterally to produce a bevel cut.
3. A device of the character described including a draw head of appreciable width and thickness having one edge adapted to engage the work, a draw handle for said head, a blade removably and adjustably mounted in said head and pro-

jecting from the work engaging edge of the same, and said edge being transversely beveled to tilt the head and blade laterally to produce a bevel cut.

4. A device of the character described including a draw head of appreciable width and thickness having one edge adapted to engage the work, a draw handle for said head, said head being formed of two connected sections, one of which is carried by the handle, a cutting blade clamped therebetween and projecting from the work engaging edge of the head, and said edge being transversely beveled to tilt the head and blade laterally to produce the bevel cut.

5. A device of the character described including a draw head of appreciable width and thickness having one edge adapted to engage the work, a draw handle for said head, said head being formed of two sections loosely connected at one end opposite the work engaging edge, a cutting blade positioned between the two sections and projecting beyond the work engaging edge, means to clamp the sections of the head together adjacent said cutting edge, and said edge being transversely beveled to tilt the head and blade laterally to produce a bevel cut.

6. A device of the character described including a draw head of appreciable width and thickness having one edge adapted to engage the work, a draw handle for said head, a blade projecting from the work engaging edge of the head, and means on the work engaging edge of the head to tilt the head and blade laterally to produce a bevel cut.
